[57] CLAIM

The ornamental design for a photograph album cover,
as shown and described.

DESCRIPTION

FIG. 1 is a front elevational view of a photograph
album cover showing my new design;

FIG. 2 is a right side elevational view thereof, the left
side view being a mirror image thereof;

FIG. 3 is a bottom plan view thereof, the top view being
a mirror image thereof;

FIG. 4 is a rear elevational view thereof; and

FIG. 5 is a front elevational view of a photograph
album cover showing a modification of my new design.
The back, top, bottom, left side and right side views of
the embodiment of FIG. 5 are identical to the corre-
sponding views of the embodiment of FIG. 1.

FIG. 1

FIG. 2

FIG. 3

FIG. 4
